US0D1001850S

(12) **United States Design Patent** (10) **Patent No.:** **US D1,001,850 S**
(45) **Date of Patent:** **** Oct. 17, 2023**

(54) **ICE MOLD**

(71) Applicant: **Shenzhen Jiameiqi Investment Consultation Co., Ltd.**, Shenzhen (CN)
(72) Inventor: **Aichun Xiong**, Hunan (CN)
(73) Assignee: **Shenzhen Jiameiqi Investment Consultation Co., Ltd.**, Shenzhen (CN)

(**) Term: **15 Years**

(21) Appl. No.: **29/876,017**

(22) Filed: **May 15, 2023**

(51) LOC (14) Cl. **07-10**
(52) U.S. Cl.

(57) **CLAIM**

The ornamental design for a ice mold, as shown and described.

DESCRIPTION

FIG. 1 is a front, left side perspective view of a ice mold, showing my new design;

FIG. 2 is a rear, right side perspective view thereof;

FIG. 3 is front, right side perspective view of the ice mold with the lower half of the case removed from view for ease of illustration;

FIG. 4 is a front elevational view of a ice mold, showing my new design;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

1 Claim, 9 Drawing Sheets
